UNITED STATES PATENT OFFICE.

JOHN L. MCKAY, OF MINNEAPOLIS, MINNESOTA.

TABLE-TOP PROTECTOR.

No. 888,113.

Specification of Letters Patent.

Patented May 19, 1908.

Application filed June 21, 1907. Serial No. 380,026.

To all whom it may concern:

Be it known that I, JOHN L. MCKAY, a citizen of the United States, residing at Minneapolis, in the county of Hennepin and State of Minnesota, have invented certain new and useful Improvements in Table-Top Protectors; and I do hereby declare the following to be a full, clear, and exact description of the invention, such as will enable others skilled in the art to which it appertains to make and use the same.

My invention has for its object to provide an improved, simple, cheap and convenient table top protector, and to this end it consists of the novel devices and combinations of devices hereinafter described and defined in the claims.

In the accompanying drawings, which illustrate the invention, like characters indicate like parts throughout the several views.

Referring to the drawings; Figure 1 is a plan view of the improved protector. Fig. 2 is an edge elevation thereof, showing the protector partially folded. Fig. 3 is an edge elevation of the protector, showing the same turned into a vertical position with the two separable sections thereof moved apart. Fig. 4 is a fragmentary perspective view of a portion of the protector, with some parts broken away and some parts loosened up and turned out of position, with the said parts viewed looking to the top of the protector. Fig. 5 is a bottom plan view of that portion of the protector which is shown in Fig. 4. Fig. 6 is a fragmentary perspective view, with some parts broken away and some parts turned from position, and illustrating particularly the manner in which the folding quadrants of a protector are connected by flexible hinges. Fig. 7 is an edge elevation, with some parts broken away, showing a device for securing together the two semi-circular sections of the protector. Fig. 8 is a fragmentary view in plan of the parts shown in Fig. 7; and Fig. 9 is a detail view in section taken on the line $x^9 x^9$ of Fig. 1, but shown on an enlarged scale.

The improved protector, herein illustrated, is shown as circular, but may, nevertheless, be square, oblong, or of any other desired form. It is made up of so-called half sections and quarter sections which, in the circular protector, may be designated respectively as semi-circular sections and quadrants, the said quadrants being designated

as entireties by the numeral 1. The main body portions of these quadrants 1 are formed by a light filler which is made up of two pasteboard plates 2 between which is secured a corrugated pasteboard spacer 3. The diverging marginal edges of this filler are reinforced by wooden slats 4, and preferably this filler is strengthened and held together by means of a sheet of heavy pasteboard 4^a. Over the entire bottom of this composite filler is secured a sheet of felt or heavy cloth 5. A sheet of asbestos cloth 6 is placed over the entire top of the said composite filler, and the edges of the felt sheet 5 are turned upward and inward and are secured to the upper marginal portion of the said asbestos sheet 6, all as best shown in Figs. 4 and 5.

A sheet of oil cloth 7 is extended over two of the quadrants thus formed and is secured to the upper surfaces of the sheets 6 and to the upper surfaces of the inturned upper edges of the felt facing 5. The oil cloth sheets 7 thus flexibly connect the four quadrants of the protector in two pairs, and in a sense afford the hinges therefor. However, the said quadrants are further connected by leather hinges 8 that are directly applied to the upper surfaces of the abutting edges of the asbestos sheets 6 of the connected quadrants by means of tacks, or other suitable means. Furthermore, flexible reinforcing joint strips 9 overlap the joints between the flexibly connected quadrants, and are secured by adherent material, or other means, over the hinges 8 and between the abutting asbestos sheets 6 and the oil cloth covering 7. These reinforcing joint strips 9 should be of waterproof material, such, for instance, as oil cloth or rubber sheeting, so that besides reinforcing the flexible hinges, they afford additional protection against the passage of liquids between the joints of the protector even though the oil cloth should be cracked in the line of the joints.

The oil cloth covering 7 of one of the semi-circular sections, made up of a pair of connected quadrants, is provided with a projected flap 7^a that is adapted to overlap the abutting edge of the other oil cloth covering, and thus form an approximately liquid tight joint between the two semi-circular or half sections of the protector.

When the two half sections of the protector are placed together upon the table top, fastenings for securing the same together are

desirable, and these fastenings should be such that they will not scratch or mar the top of a highly polished table. Hence, I provide one of the half sections with flexible cords 10 of leather, or other suitable material, and provide the other half section of the protector with coöperating spring clips or prongs 11 having diverging tongues, as shown in Figs. 7 and 8. By reference to these views it will be seen that the two half sections of the protector may be secured together by drawing the free ends of the so-called cords 10 between the bodies and tongues of the said clips. With these fasteners also, it is evident, the two half sections of the protector may be very quickly disconnected.

What I claim is:

1. A sectional table top protector, the sections of which are provided with covering sheets, one of which has a projecting edge flap adapted to overlap the abutting edge of an adjacent section, substantially as described.

2. A table top protector made up of quarter sections, said quarter sections being connected in pairs for folding movements and each connected pair having a flexible covering one of the said flexible coverings having a projecting edge flap that is adapted to overlap the abutting edges of the other pair of quarter sections, substantially as described.

3. A table top protector made up of quarter sections, and flexible waterproof coverings connecting the said quarter sections in pairs, and each quarter section further comprising a corrugated filler, an asbestos covering sheet, and a felt sheet covering the bot-

tom thereof turned upward and inward and secured between the said asbestos covering and said waterproof covering, substantially as described.

4. In a table top protector, the combination with quarter sections made up of the corrugated filler 2—3, with marginal reinforcing slats 4, the asbestos sheet 6 secured to the upper surfaces of said filler, the waterproof covering 7 connecting said quarter sections in pairs, and the felt sheets 5 applied to the under surfaces of said quarter sections with their edges turned upward and inward and secured between the said asbestos sheet 6 and waterproof covering 7, substantially as described.

5. A table top protector made in separable half sections, and each half section comprising a filler or body portion, hinges 8 connecting the said quarter sections in pairs, waterproof reinforcing strips 9 overlapping said hinges and joints of the sections connected thereby, and waterproof coverings overlying said joint strips and covering the connected sections, substantially as described.

6. The combination with a sectional table top protector, of spring tongues or clips applied to one of the sections thereof, and flexible cords connected to the other section thereof and detachably engageable with said tongues, substantially as described.

In testimony whereof I affix my signature in presence of two witnesses.

JOHN L. MCKAY.
